UNITED STATES PATENT OFFICE.

MERTON W. WILLMORE, OF CINCINNATI, OHIO, ASSIGNOR TO THE GIBSON ART COMPANY, OF CINCINNATI, OHIO, A CORPORATION OF OHIO.

NOVELTY CARD AND DEVICE.

Application filed May 21, 1927. Serial No. 193,330.

My invention relates to art and novelty cards and devices.

It is the object of my invention to provide an art card having a portion which may be moved around a substantially fixed center and which will disclose slogans, articles, poems or other inscriptions, on an area on a normally concealed immovable portion. It is further my object to make such devices from units consisting of a background board and a movable front portion in which the background has a slot through which the front member gradually disappears, as it is advanced from one position to another, exposing the concealed inscriptions or articles.

The above and other objects which will be noted during the ensuing disclosure I accomplish by that certain arrangement and combination of parts of which I have shown a preferred embodiment.

In the drawings:—

Figure 1 is a front elevation of an art card having portions representing the dial of a clock, with the portion movable about a fixed center shown in fully closed position.

Figure 2 is a front elevation of the same card shown in Figure 1, with the movable member one quarter open showing several inscriptions on the background.

Figure 3 is a section along the lines 3—3 in Figure 2.

Figure 4 is a front elevation of the movable member removed from the background supporting piece.

Figure 5 is a front elevation of a card which is decorated in a different manner, and in which a series of movable members representing portions of flowers are shown.

Generally indicated at 1 is the background piece having a slot 2 extending across it. In this instance the slot extends radially from the center 3 about which the member 4 moves. The movable member, as shown in Figure 4, also has a slot 5 which allows a sector thereof to seat within the slot 2 of the background.

The center 3 about which the member 4 moves is usually provided with a rivet which extends through both the member 4 and the background member 1. The area which is concealed under the movable member is usually provided with inscriptions which refer to the purpose of the card, or which are in keeping with the decorations with which the card

is embellished. While I have shown only printed inscriptions on the background member, there may also be objects either secured flat against the background or disposed in pockets therein.

There are an infinite variety of decorative effects which may be produced, such as coin safes, candy suckers, radio logging devices and the like, and while I have shown only a clock card and a flower basket card, I do not wish to be limited to the particular decorations as shown. The use of a member movable about a central point which may be turned and which sector by sector slides within a slot in the background is a mechanical arrangement which may be copied in a wide variety of forms.

The movable member or members each has a hub portion 6, partially cut out with a circular cut 7, the cut 7 forming a continuation of the slot 5. The end of the cut 7 acts as a stop to limit the movement of the movable member.

It is preferable to provide the member which is movable about a fixed center with a small extension or tongue 8, which will act as a stop to prevent the member from sliding through the slot in the background. The movable members may be cut out from a paper blank with one operation, the line of cut extended in all the members in a substantially similar manner. The background piece may also be cut out with one operation, and the problem of assembling is very simple, all the labor required being the insertion of the tongue 8 and the sector edge indicated at 9 in Figure 4 within a slot, and the insertion of the rivet 3 at the fixed center about which the members 4 are movable.

Having thus described my invention what I claim as new and desire to secure by Letters Patent is:—

1. In combination with a slotted background piece, a member having a sector slidably mounted within the slot, said background piece having concealable portions bearing announcements and covered by said member in the fully exposed position thereof, and said member pivoted on said background piece, and said member provided with means for limiting the range of movement thereof within said slot.

2. In combination with a slotted back-

background piece, a member having a sector slidably mounted within the slot, said background piece having concealable portions bearing announcements and covered by said member in the fully exposed position thereof, and said member pivoted on said background piece, said member provided with means

for limiting the range of movement thereof within said slot, and the announcements arranged in a sequence and progressively revealed by the movement of the member within said slot. ¹⁰

MERTON W. WILLMORE.
